UNITED STATES PATENT OFFICE

GRANT CAMPBELL, OF SHORT HILLS, NEW JERSEY

LIQUID-RELIEF VALVE

Application filed August 26, 1926. Serial No. 131,645.

This invention is a novel liquid relief valve adapted to receive any liquid or condensate, such as water, from any vessel or passage, such as a steam pipe, and automatically to discharge the received or accumulated liquid under control of the liquid itself or the extent of accumulation thereof. The field of utility of a valve or trap of this class is very large, but the particular design or structure of valve illustrated in the drawings is intended more especially for use with steam heating systems such for example as those used in heating the cars of railroad trains. The preferred manner of combining the valve with the passages and other elements of the steam heating system is not herein indicated, but is shown in a pending application.

The general objects of the present invention are to improve the efficiency of operation of relief valves, to improve the reliability of the automatic discharging action, and to afford simplicity and ease of installation and adjustment along with ruggedness and durability of structure.

Other and further objects and advantages of the present invention will be explained in the hereinafter following description or will be apparent to those skilled in the subject. To the attainment of the objects and advantages referred to the present invention consists in the liquid relief valve and the novel features of operation, arrangement, combination, structure and detail herein illustrated or described.

In the accompanying drawings Fig. 1 may be considered a vertical central section of an automatic relief valve embodying the principles of the present invention, although the illustrated valve is not necessarily to be employed in the upright position shown in the figure.

Fig. 2 is a right hand elevation of the valve shown in Fig. 1.

Fig. 3 is a top plan view of the valve shown in Figs. 1 and 2 with half of the front or valve chamber shown in central horizontal section.

Fig. 4 is a modified detail of structure

showing a different form of inlet and orifice to the control chamber.

Fig. 5 is a modified detail showing a different form of outlet and orifice from the control chamber.

Fig. 6 is a face view of the diaphragm of Figs. 1-3 detached.

Near the center of each car in a railroad train the train pipe or main steam pipe is usually provided with a cross fitting having extensions to the radiator pipes inside the car. The present invention may be employed to drain the train pipe of condensate, and the cross connection is preferably formed with a bottom opening for this purpose, and a water pocket into which the opening drains, with an internal strainer to protect the relief valve. The vertical pipe 7 may represent this receiving water pocket or connection from the steam system of each car to the relief valve 8 of this invention. At the lower side the relief valve is shown provided with a final outlet or discharge pipe 9 which may lead to waste, or to any desired point, and may be provided with a muffler. The inlet 7 and outlet 9 may be reversible with suitable rearrangements.

The valve hereof is shown as provided with a pressure responsive device or diaphragm 10 and it is intended in using the term diaphragm to refer to a piston or other movable device responsive to pressure fluctuations. The diaphragm 10 may consist of a thin metal sheet and its rear side is shown reinforced by a diaphragm plate or disk 11, the flexing or working part of the diaphragm being that surrounding the disk. The diaphragm is shown clamped rigidly between the main valve casing or body 12 at the front and a rear casing or bonnet 13 containing the valve springs and wherein certain control is preferably effected as will be described. The control casing 13 is shown as having a centrally extending barrel in which are accommodated one or more sets of springs. There is shown a heavy or main spring 14 and a light auxiliary spring 15 cooperatively acting upon the diaphragm disk 11 and surrounding the stem of such a disk. A spring plate or adjusting disk 16 is arranged at the rear ends of the springs 100

and this may be adjusted inwardly to increase the compression, and vice versa, by means of a screw 17 having a lock nut 18 holding it in the desired adjustment.

5 Inside the body or casing 12 is the valve chamber 19 and from the casing projects inwardly a post or extension 20 having an outlet passage or bore 21, the inner extremity of which is fitted with a valve seat or nozzle 22, 10 the passage within which is preferably at right angles to the diaphragm 10 and the effective or seating surface of which is parallel with the diaphragm. Opposite to the valve seat 22 is the movable valve member 23, which 15 may consist of a simple flat disk supported in a movable head 24, and clamped in the recess of the head by an apertured nut or retaining ring 25. The head 24 is formed with an outstanding stem 26 by which it is guided 20 as the valve more or less opens or closes. The stem 26 is provided with a longitudinal passage 27 connecting with a lateral passage 28 by which the pressure in the valve chamber 19 may be communicated to the space at the 25 end of the stem 26 to preclude the effect of a dash pot.

The valve disk 23 and its carrying head 24 are mounted at the forward end of a yoke 30 attached at the forward side of the diaphragm 10, its threaded shank extending 30 through into clamping engagement with the diaphragm disk 11. The yoke 30 extends forwardly at both sides of the projection 20 and the two sides of the yoke are connected by a 35 top piece or arch 31, so that in front view the yoke will take substantially the shape of the letter U inverted. The valve disk head 24 is connected to the arch by a set screw 32 as seen in Fig. 1, and at the two sides are 40 set screws 33, as seen in Fig. 3. These described parts may be accessible through a removable cap 35 having a screw engagement with the body 12. This screw cap has an inwardly extending barrel 36 forming a guide 45 for the stem 26 of the head 24, while the barrel is surrounded by a compressed spring 37 pressing rearwardly against the head and tending to close the valve by forcing the disk 23 towards the seat 22.

50 It will be observed that the adjustment of the valve is controlled by the position of the diaphragm which in turn is determined by the existing train pipe pressure in the chamber 19 opposed by the existing pressure in the chamber 38 and modified by the permanent pressures of the contained springs 14, 55 15 and 37. In accordance with this invention the rear chamber 38 is employed as a valve controlling chamber, for example by continually passing into and from the chamber 60 hot water or steam or a combination of them, namely by means of inlet and outlet orifices or equivalent progressive escape devices, and utilizing the varying resulting pressure in the 65 control chamber by applying it to the sensi-

tive diaphragm to effect the partial or total closing or opening of the valve 22, 23. When water or condensate enters the relief valve in excess it fills the valve chamber and then passes over into the control chamber, which 70 is at a depressed pressure, resulting in re-evaporation of the hot water and a consequent rise of control chamber pressure as compared with the conditions when water is not in excess and steam only passes over 75 from the valve chamber to the control chamber. The inlet orifice will carry into the control chamber far larger quantities of water by weight, and a far larger quantity of heat, than when steam only traverses the orifice, 80 this being due to the well known restrictive action of the orifice upon flow of steam or other gas.

The orifices and connecting passages may be advantageously and compactly provided 85 as follows. A vertical bore or passage 39 is shown formed in the upper part of the rear casing 13 extending from the periphery into the control chamber 38; while a similar vertical passage 40 is shown formed in the lower 90 part of the same casing; the two passages 39 and 40 being exteriorly closed by plugs 41.

A horizontal passage 42 leading to the inlet orifice 48 may be formed as a horizontal bore through the casing 13, stopped by an 95 external plug 44, while a similar horizontal passage 43 may be provided at the lower part of the casing in connection with the outlet orifice, this also stopped by a plug 44. In alignment with the passages 42 and 43 there 100 are shown bores or passages 45 and 46 produced at the rear side of the valve casing 12, the upper passage 45 connecting with the upper part of the valve chamber, while the lower passage 46 connects with the outlet 105 passage 21 leading to the discharge pipe 9. An inlet orifice 48 is shown interposed in line with the upper passages 45 and 42, while an outlet orifice 49 is similarly interposed between the lower passages 43 and 46. The sizes 110 of the orifices will vary in accordance with the expected pressures, but preferably the outlet orifice has a larger area than the inlet orifice.

An advantageous way of producing the 115 inlet and outlet orifices is by so extending the piece of sheet metal 10 which constitutes the diaphragm as to stand across the orifice passages, and forming the orifices by punctures 120 in such sheet metal diaphragm. The arrangement indicated in the figures may be varied. Thus as indicated in Fig. 4 the passages 45 and 42 may be omitted and the inlet orifice 48^a may be formed directly in the annular or flexing portion of the diaphragm 10^a clamped between the casings 12^a and 13^a. On the other hand the outlet orifice instead 125 of discharging through passage 46 into the same final discharge pipe 9 which receives the discharge of the valve may discharge di- 130

rectly into the atmosphere through an orifice piece 49^a as indicated in Fig. 5, this being substituted for the lower closing plug 44 at the rear side of the rear casing 13^a. The outgoing hot vapors instead of passing directly to waste may be, first directed into a heating coil or pipe in the car for heating purposes.

Various modifications are available within the principles of the invention. Since the chamber 38 operates as a vaporization chamber for the excess hot water received through the inlet orifice 48 provision may be made to prevent undue cooling in the coldest weather. It may be desirable to change the action by 15 altering the sizes of the orifices 48 and 49, and in the form shown in Figs. 1-3 this may be accomplished, as shown in Fig. 6, by providing orifices 42 42^a etc., 43, 43^a etc. of varying sizes around the periphery of the dia- 20 phragm 10 which has thus only to be shifted to bring the desired orifices into the inlet and outlet passages. In referring to an orifice it is intended to cover any equivalent progressive escape means. Thus instead of a single 25 aperture there might be employed a plurality of apertures having the equivalent discharge area, or even a multiplicity of small openings.

As an instance or embodiment of the illus- 30 trated relief valve, the diaphragm may have an effective area of say 5 square inches. The forward pressure on the diaphragm of the combined springs may total 37.5 pounds, thus offsetting a fluid pressure of 7.5 pounds per 35 square inch on the front side of the dia- phragm. This setting may for example serve to cause valve control actions with train pipe pressures from 50 down to 10 pounds per square inch. The orifices may be of progres- 40 sively increasing sizes, for example the inlet orifice 0.050 inch in diameter and the outlet orifice 0.066 inch, or other sizes with similar area ratios, a smaller size keeping down the rate of continuous flow through the system. 45 The control chamber 38 will constantly contain fluid under a pressure substantially lower than that in the valve chamber. The controlling factor is the difference between the existing full pressure in the pocket or pipe 7 in any car, communicating with the chamber 19, and the existing depressed pressure in the control chamber 38. Taking the case of a middle car, with train pressure between 10 and 50 pounds, say 30 pounds, the spring pres- 50 sure is such that when steam only traverses the first orifice 48 the pressure difference will suffice to overcome the springs and close the valve. For example this minimum depressed pressure may be as low as 11 pounds and the 55 preponderating pressure of 19 pounds at the forward side of the diaphragm will overbalance the springs and tightly close the valve disk 23 against the seat 22. When condensate accumulates it will gradually fill up the 60 chamber 19 and when this condensate or hot 65

water has access to the orifice 48 it will pass through into the control chamber. There it substantially or wholly reevaporates due to the lower pressure, and thus raises the depressed pressure to such an extent that, aided 70 by the springs, it overbalances the 30 pounds full pressure and moves the diaphragm forwardly to open the valve. This is the operation with all train pressure between 10 and 50 pounds. If the existing pressure at a 75 front car is above 50 pounds, the depressed pressure will never rise enough to overbalance and open the valve; but the condensation is less at this point due to the hotter temperature, and the continued discharge 80 through the orifice system will usually dispose of the probable amount of condensate. However, if a higher range of pressure is required this can be obtained by placing a higher compression on the springs, and modifying the orifice areas or ratio if necessary. 85

It will be understood that the existing train pipe pressure at any car is progressively lower from the forward end of the train, where the source of steam is located, toward the rear end. The relief valve hereof adapts its action to its position in the train so that in making up trains or reversing engines no attention need be given to the valve, or its adjustment, except under extraordinary conditions. In cars having pressures between 10 and 50 pounds, say 30 pounds, when water is not in excess, or immediately after a discharge of water, steam only will pass through the first orifice. It expands in traversing the orifice but the inflow is restricted and a low control pressure results so that the full train pipe pressure in the valve chamber causes the tight closing of the valve and there will be no direct loss or escape of steam. The steam passing through the orifice system, referring to the two orifices and the chamber between them, is so small in total amount as to be negligible, and can be utilized as suggested. When the accumulating water in the valve reaches the inlet orifice it passes into the chamber and creates the higher depressed pressure, above 22.5 pounds, so that by cooperation with the springs the valve is opened, giving a direct discharge of water by way of the relief valve, which may be practically continuous when much condensate has to be disposed of. Thus the condensate is never allowed to rise above the inlet orifice level, and so the train pipe is kept dry. 110

At the rear cars of the train the existing full pressure may be so low, namely, below 10 pounds, as to be unable to overcome the springs plus the opposing depressed pressure in the control chamber, so that the valve remains always open, giving a constant slight blow off of low pressure steam both at the valve and through the orifice system, as is de- 115 120 125 130

sirable to maintain the heating system in action and the train pipe free of condensate.

The orifice system is shown as containing two orifices, but might contain more, in tandem, the final one being preferably the largest, and discharging to atmospheric or comparably low pressure. The final discharge may be into the heating pipes of the car because the heating pressure is low due to the common use of a pressure reducer or vapor regulator between the train pipe and heating pipes. For example the outlet 9 from the relief valve may extend to the inlet of the car heating pipes. This utilizes the heat of the outlet steam and combines the final water discharge with that from the heating coils.

There has thus been described a liquid relief valve or trap embodying the principles and attaining the objects of the present invention; but since various matters of operation, arrangement, combination, structure and detail may be modified without departing from the principles, it is not intended to limit the invention to such matters except so far as set forth in the appended claims.

What is claimed is:

1. Apparatus for automatically discharging accumulated condensate comprising a collecting passage, a relief valve arranged to receive and discharge condensate and having a pressure sensitive device controlling it, a chamber at one side of said sensitive device delivering full pressure thereto, and a chamber at the other side delivering depressed pressure thereto, a connection conducting condensate to the second chamber with restricted inlet thereto, and a continuously open restricted outlet from said second chamber.

2. Apparatus for automatically discharging accumulated condensate comprising a collecting passage, a relief valve arranged to receive and discharge condensate and having a pressure sensitive device controlling it, a chamber at one side of said sensitive device delivering full pressure thereto, and a chamber at the other side delivering depressed pressure thereto, a connection conducting condensate to the second chamber with restricted inlet, a restricted outlet from said second chamber, and means working with the depressed pressure to keep open the relief valve except when the full pressure is greatly in excess of the depressed pressure.

3. A relief valve for relieving mixed fluid of excess liquid comprising a casing containing a pressure sensitive device with a valve chamber at one side thereof and a control chamber at the other side, passages conducting fluid to the valve chamber and conducting excess liquid to the control chamber through an interposed orifice, an orifice outlet from the control chamber permitting continuous escape from the control chamber dur-

ing admission of liquid thereto through the first orifice, a valve arranged for discharging liquid from the valve chamber, and a connection whereby the sensitive device adjusts the valve to discharge liquid when in excess and vice versa.

4. Liquid relief apparatus for automatically discharging accumulated liquid comprising a valve casing containing a valve chamber and a control chamber separated by a pressure sensitive device, a valve means in said valve chamber arranged to be controlled by the movements of the sensitive device and adapted bodily to discharge accumulated liquid, an orifice connection from the valve chamber to the control chamber and a continuously open orifice outlet from the control chamber.

5. Liquid relief apparatus for automatically discharging accumulated condensate comprising a valve casing containing a valve chamber and a vaporization chamber separated by a pressure sensitive device, a valve means in said valve chamber arranged to be controlled by the movements of the sensitive device and adapted bodily to discharge accumulated liquid, an orifice connection from the valve chamber to the vaporization chamber and an orifice outlet from the vaporization chamber; whereby constant flow occurs through the vaporization chamber to the atmosphere, whereas direct discharge through the valve chamber occurs only as permitted by or under control of the diaphragm.

6. Apparatus as in claim 5 and wherein both the orifice inlet to and orifice outlet from the vaporization chamber are formed in chamber-to-chamber passages in the casting walls.

7. Liquid relief apparatus for automatically discharging accumulated hot liquid comprising a valve casing containing a valve chamber and a vaporization chamber with a pressure sensitive device separating them, a valve means in said valve chamber arranged to be controlled by the movements of the sensitive device and adapted bodily to discharge accumulated liquid, an orifice formed directly in the sensitive device for connection from the valve chamber to the vaporization chamber and a continuously open orifice outlet from the control chamber, whereby when the hot liquid is in excess it may pass the orifice inlet for evaporation in the vaporization chamber to raise the pressure therein and open the valve.

8. Liquid relief apparatus for automatically discharging accumulated liquid comprising a walled valve casing containing a valve chamber and a control chamber separated by a pressure sensitive device, a valve means in said valve chamber arranged to be controlled by the movements of the sensitive device and adapted bodily to discharge accumulated liquid, an orifice connection

formed in the casing walls and connecting the valve chamber to the control chamber, and an orifice outlet from the control chamber.

9. Apparatus as in claim 8 and wherein the first orifice connection in the casing walls is formed near the upper part of the valve chamber, whereby liquid will not traverse the same until the valve chamber fills up.

10. Liquid relief apparatus for automatically discharging accumulated liquid comprising a walled casing containing a valve chamber and a control chamber, with a pressure sensitive diaphragm separating them, a valve means in said valve chamber arranged to be controlled by the movements of the diaphragm and adapted bodily to discharge accumulated liquid, an orifice connection from the valve chamber to the control chamber and an orifice outlet from the control chamber; the first orifice connection being formed in the casing walls, and the orifice itself being an extension of the diaphragm extending into the casing walls.

11. Liquid relief apparatus for automatically discharging accumulated liquid comprising a valve casing containing a valve chamber and a control chamber separated by a pressure sensitive device, a valve means in said valve chamber arranged to be controlled by the movements of the sensitive device and adapted bodily to discharge accumulated liquid, an orifice connection from the valve chamber to the control chamber, and an orifice outlet from the control chamber arranged in the casing walls and discharging into the valve chamber discharge outlet.

12. Relief apparatus for automatically discharging accumulated hot condensate comprising a collecting passage, a relief valve arranged to receive and discharge condensate and having a pressure sensitive device controlling it, a chamber at one side of said sensitive device delivering full pressure thereto, and a vaporization chamber at the other side delivering depressed pressure thereto, a connection conducting excess condensate to the vaporization chamber with a restricted inlet thereto, and a restricted outlet from said second chamber.

13. Liquid relief apparatus for automatically discharging accumulated liquid comprising a collecting passage, a relief valve arranged to receive and discharge the liquid and having a pressure sensitive device controlling it, a first chamber at one side of said sensitive device delivering full pressure thereto, and a chamber at the other side delivering depressed pressure thereto, a connection conducting condensate to the second chamber with restricted inlet thereto, and a restricted outlet from said second chamber, whereby the second chamber pressure varies and excess pressure therein actuates the sensitive device to open the discharge valve.

14. Relief apparatus for automatically discharging accumulated steam condensate comprising a valve casing containing a valve chamber and a vaporization chamber with a pressure sensitive device separating them, a valve means in said valve chamber arranged to be opened by approaching movement of the sensitive device and vice versa and adapted to discharge condensate, a constantly open orifice connection from a high point in the valve chamber to the control chamber and a constantly open orifice outlet from the control chamber.

In testimony whereof, I have affixed my signature hereto.
